DESIGN FOR A FLOOR MAT

Laurence M. Oakley, Trenton, N. J., assignor to
Essex Rubber Company, Trenton, N. J., a cor-
poration of New Jersey

Application June 19, 1940, Serial No. 93,097

Term of patent 14 years

To all whom it may concern:

Be it known that I, Laurence M. Oakley, a citizen of the United States, residing at Trenton, in the county of Mercer and State of New Jersey, have invented a new, original, and ornamental Design for a Floor Mat, of which the following is a specification, reference being had to the accompanying drawing, forming part thereof.

Figure 1 is a plan view of a floor mat showing my new design, and

Figure 2 is a section on the line 2—2 of Figure 1.

The portion of the mat not shown is a mere continuation of the portions shown and is formed in the same manner.

I claim:

The ornamental design for a floor mat, as shown and described.

LAURENCE M. OAKLEY.
